UNITED STATES PATENT OFFICE

2,601,772

KNITTED NECKWEAR

Benjamin Mendelsohn, New York, N.Y.

Application June 23, 1950, Serial No. 169,809

4 Claims. (Cl. 66—171)

1

This invention relates to new and useful improvements in the construction of knitted neckties.

Knitted ties as known heretofore are constructed in tubular form or in a flat form wherein threads of different weights are utilized to provide the narrow and the wide portions of the tie.

It has been found that the tubular tie construction is unsatisfactory in that the double thickness of material prevents the forming of a small, neat knot therewith; and the known flat construction is unsatisfactory in that the means for forming the same must be capable of handling a plurality of threads of different weights.

One object of the invention is the provision of a knitted tie of flat construction in which all of the thread is of one thickness.

Another object of the invention is to construct the tie so that the same has a narrow portion for the back of the wearer's neck and for knot forming, and a wider frontal portion.

Another object of the present invention proposes the knitting of a single layer tie which will require conventional finish seaming only at its short end and which has its long end and both of its longitudinal sides formed with a selvage.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the tie of the invention.

Fig. 2 is a fragmentary enlarged face view of a portion of the tie illustrated in Fig. 1.

Fig. 3 is a fragmentary partially diagrammatic sectional view on line 3—3 of Fig. 2.

Referring to Fig. 1, the tie of the invention comprises a wide frontal portion 10, a back of the neck and knot forming narrow portion 11, and a tail portion 12 wider than portion 11 but narrower than the front portion 10.

The tie is formed on an ordinary flat knitting machine with a plurality of longitudinal wales 13, see also Figs. 2 and 3, the outermost ones of which are bounded by the usual end loops 14 providing a selvage along the two longitudinal sides of the tie.

In Fig. 2 the stitching of the wales 13 is shown somewhat diagrammatically by herringboned

2

lines; and in Fig. 3 the sectioning for ordinary fabric is utilized. This manner of illustration is deemed desirable in view of the fact that the stitching involved in the tie is of the ordinary kind and is extremely familiar to those skilled in the art.

In order to decrease the width of the tie to form portion 11, the machine needles concerned with knitting the outermost wales 13 are dropped at the appropriate time to end said wales at the points 15, see Fig. 2. Then a few courses later the new outermost wales are ended as at 16, also by dropping the appropriate needles. By this method the number of wales and therefore the width of the tie is decreased gradually until only the desired number of wales remains. Thus the number of wales in the narrow portion 11 is substantially less than that in the frontal portion 10.

To form the tail portion 12 one or more pairs of the dropped needles are reenabled to form added wales.

It will be seen, therefore, that the tie of the invention is of flat construction and is formed with wide and narrow portions merely by omitting or adding wales through the manipulation of the appropriate machine needles. Knitting is started at the front portion 10 forming a selvage 10a at the end of the front portion, so that when knitting is completed the tie will have selvedges at the long end and the two longitudinal sides. The tie is finished by finish seaming at the end 12a of the tail portion 12. In the knitting of conventional tubular ties it is necessary to finish seam the two ends of the tie as only the longitudinal sides of the tie have selvedges.

On the drawing, the front portion 10 and the tail portion 12 are knit so as to have a plain appearance, but it is appreciated that those portions could be knit to include any desired decorative pattern. For instance, the portions 10 and 12 could be knit to have alternate laterally extending or alternate diagonally extending strips formed of differently colored threads, as is generally known in the art to which the present invention pertains.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I

claim as new, and desire to secure by United States Letters Patent is:

1. A flat knitted tie comprising a single ply of knit material having a wide frontal portion, a narrow knotting and back of the neck portion, and a tail portion wider than the said narrow portion but narrower than the said wide portion, the tie being formed with longitudinal wales, the ending of the outermost pairs of which forms said narrow portion.

2. A flat knitted tie comprising a single ply of knit material having a wide frontal portion, a narrow knotting and back of the neck portion, and a tail portion wider than the said narrow portion but narrower than the said wide portion, the tie being formed with longitudinal wales of which the outermost pairs are ended successively to form said narrow portion.

3. A flat knitted tie comprising a single ply of knit material having a wide frontal portion, a narrow knotting and back of the neck portion, and a tail portion wider than the said narrow portion but narrower than the said wide portion, the tie being formed with longitudinal wales of which the outermost pairs are ended successively to form said narrow portion, the tail portion being formed by adding one or more wales to those also in the narrow portion.

5. A flat knitted tie comprising a single ply of knit material having a wide frontal portion, a narrow knotting and back of the neck portion, and a tail portion wider than the said narrow portion but narrower than the said wide portion, the tie being formed with longitudinal wales, the ending of the outermost pairs of which forms said narrow portion, and the addition of one or more pairs of which to those in the narrow portion forms the tail portion.

10 BENJAMIN MENDELSOHN.
